UNITED STATES PATENT OFFICE

ARTHUR W. BRICE, OF ROCHESTER, AND WILLIAM HAMANN, OF IRONDEQUOIT, NEW YORK, ASSIGNEES TO UNITED SHOE MACHINERY CORPORATION, OF PATERSON, NEW JERSEY, A CORPORATION OF NEW JERSEY

SHOE-FINISHING MACHINE

Application filed November 3, 1922, Serial No. 598,837. Renewed December 26, 1928.

This invention relates to shoe-finishing machines and is herein illustrated as embodied in a machine for burnishing or setting the edges of shoe soles.

Various shoe-finishing machines are provided with several tools which are brought into use alternately, as by mounting the tools on a holder which may be moved to bring one after another of the tools into operative position. An example of this is found in edge setting machines in which commonly an oscillating tool holder is provided having forepart and shank tools which can be alternately brought into working position. Some of these machines, to effect the exchange of tools, require the operator to let go of the shoe with one hand in order to unlock the tool holder and turn it manually to the desired position. This slows down the work considerably since the tools are usually changed once for every shoe. Other machines, although they do not require the operator to let go of the shoe, nevertheless require him to change position or balance in order to push with knee or hand against a lever which, through more or less complicated mechanism, effects the interchange of the tools. This change of position or of balance and the effort required constitute a serious hindrance to rapid work. Moreover, edge setting machines are run at very high speeds and the tool holders, which are frequently not balanced with respect to their axes of oscillation, are liable to produce so much vibration that the working stroke of the tool is affected. This furnishes an added distraction to the operator both on account of the difficulty of holding the work and on account of the noise produced. The quality of work is not as good and the wear of the machine is increased.

One of the objects of the invention is to provide an improved machine of the type referred to which will be organized to operate with a minimum of vibration and allow the interchange of the tools quickly and easily, thus obviating or minimizing the above noted and other disadvantages of prior constructions. In the illustrated machine, in accordance with a feature of the invention, a bal-

anced or symmetrical tool holder is turned to change the tools by means, including a one-way clutch, utilizing the power of the machine itself when such action is permitted by the operator under control of an easily actuated latch. This means is organized automatically to energize a spring by oscillations of the shaft in one direction and when the spring is wound up, the clutch is rendered temporarily ineffective until the stored up energy has been utilized to rotate the tool holder. To effect actuation of the latch with the least disturbance to the operator, the illustrated latch extends to a point in front of the operator and at the center of oscillation of the tool holder, a light tap of the shoe or the hand against the latch being all that is needed to effect interchange of the tools. Preferably too, as illustrated and in accordance with a further feature of the invention, the tool holder is swivelled on its axis of oscillation and the tools are oppositely mounted in balanced relation to this axis to reduce vibration and noise. In the illustrated construction, the tools are each mounted at an inclination to the tool holder and thus with their longitudinal axes at a small angle to said holder. This brings the end of the lowermost tool, which is in operative position, forward toward the operator so that a shoe held in the operator's hands may be held up against the tool conveniently and with a minimum of effort.

As is well known in the art, considerable difficulty has been experienced in heating a rapidly oscillating tool, by a heating unit on the oscillating tool or holder, on account of the disintegration of the connections from the fixed frame. Another object of the invention is to furnish improved electric heating means for an oscillating tool. To this end, the illustrated machine is provided with improved heating means comprising a heating unit mounted for sliding adjustment on the frame to a position close to the path of travel of the tool to heat the same by radiation, there being preferably a lever to move the unit along the slide to vary the amount of heat transmitted. Preferably both tools are continuously heated, a shield enclosing the

tool not in use and its heating unit to retain the heat and protect the operator.

Such a location of the heating unit closely adjacent to the operating tool introduces, however, the additional danger that the operator may accidentally injure his hand or the work itself by contact with the heating unit. In order to minimize the danger, we provide, according to the preferred embodiment of the invention, a floating support for the heating means, which preferably takes the form of a swivel mounting combined with a spring-pressed restraining member which is arranged to hold the heating means yieldingly in normal position so that accidental contact will push the latter aside. By thus avoiding too firm a contact between the work, for example, and the heating means, a minimum of resultant damage will be caused.

The above and other features and advantages of the invention will appear from a consideration of the following specification and accompanying drawings in which,

Fig. 1 is a longitudinal, sectional view of a machine embodying the invention in a preferred form, showing one of the tool holders in side elevation, the other tool holder being omitted;

Fig. 2 is a top plan view of the tool holder with the enclosing casing omitted and with parts broken away;

Fig. 3 is a front elevation of the tool holder;

Fig. 4 is a vertical, transverse section of a portion of the operating mechanism for the tool shaft;

Fig. 5 is an exploded view of certain details;

Fig. 6 is a vertical, longitudinal section of the tool holder and associated parts;

Fig. 7 is a horizontal section of a portion of the same mechanism;

Fig. 8 is a vertical section on the line 8—8 of Fig. 6;

Fig. 9 is a vertical section on the line 9—9 of Fig. 6;

Fig. 10 is a view similar to Fig. 9 with some of the parts in different positions;

Fig. 11 is a vertical section of a floating mounting for the heating means; and

Fig. 12 is a perspective view of a detail.

The edge setting machine herein shown is a twin machine, each tool holder having a pair of opposite tools, one tool being a shank and the other a forepart edge setting iron. Other, or additional, tools may be used as the invention is not limited in respect to the number or character of the tools. Within a hollow frame or casing 12 is a rock shaft 14 to which is secured a rocker lever 16 pivotally connected at its end to a wrist pin 18 on the end of a connecting rod 20. The rod 20 has a strap portion surrounding an eccentric 22 on a rotary driven shaft 24 having horizontal

bearings in pillow blocks 26 projecting upwardly from the frame. The shaft 24 has a sprocket wheel 28 driven by a chain 30 from a sprocket wheel 32 on the end of the shaft of an electric motor 34 mounted on an adjustable shelf 36 on the frame cover. A casing 38 projecting upwardly from the frame cover houses the sprocket wheel 32 and the chain 30, and access to the interior of the casing may be had through a detachable cap piece 40. A rod 42 extends forwardly from the machine frame, and to this is secured the usual finger piece 44 for aiding the operator in guiding the work. The rock shaft 14 is carried in bushings 46 and 48 fixed in the frame, a collar 50 pinned to the shaft preventing movement in one direction, whereas a collar 52 (Fig. 6) threaded on the shaft at the other end of the bushing 46 prevents movement in the other direction.

Each double tool holder 54 is swivelled on a bushing at one end of the rock shaft 14 and comprises a pair of oppositely extending hollow arms in which are mounted hollow plungers 56 having keyways 58 for flat plates 60 which are attached to the tool holder and prevent the plungers from rotating. The tool holder construction is, therefore, substantially symmetrical with respect to the axis of the rock shaft, thereby reducing vibration to a minimum. Springs 62 interposed between the hub of the tool holder and the plungers hold the plungers normally in an outward position and allow the tools to yield under pressure of the work. Projecting forwardly at a small angle to the plungers are studs 64 on which forepart and shank edge setting tools 66 and 68, respectively, are mounted, being retained by spring clips of usual form. The resulting inclination of the studs 64 brings the working faces of the tools to such a working position that shoes may be easily presented thereto. To get the same result with a tool holder in which the tools are mounted at right angles to the axes of oscillation would require an inclined rock shaft. It will be noted also that inasmuch as the tools are oppositely disposed at similar inclinations, the balance of the tool holder is unaffected by this relationship.

Each tool holder can be locked to the shaft to oscillate with it and can be released for rotation to interchange the forepart and shank tools. This interchange of tools is effected through means including a one-way clutch by power supplied by the machine itself when the tool holder locking means, to be described, is unlocked. Fixed to rock shaft 14 by means of the plate 70 (Fig. 2) is a cup-shaped member 72 having at its front edge a circular flange 74 with opposite notches 76, 76 (Figs. 2 and 7) for cooperation with a latch on the tool holder. As shown best at 78 in Fig. 1 the flange 74 is inclined somewhat toward the leading edge

of the notch in order that the latch may be guided into the notch and be positively stopped without overrunning. Projecting from the tool holder is a pair of ears 80 (Figs. 1, 2 and 3) joined by a pivot pin 82 for a latch 84, the handle end of which extends to the front of the tool holder at the axis of rotation and oscillation, the other end 86 (Fig. 1) of the latch being beveled for engagement with the notches 76. To reduce friction between the tool holder locking latch 84 and the flange 74 when the tool holder is rotating, a roll 88 (Fig. 2) is pivotally mounted on the latch. A spring 90 is inserted in a hollow pin 91 abutting against the tool holder and slideable loosely in an opening of the latch, the spring abutting against a lug on the latch and being normally effective to press the end 86 of the latch into one of the notches. When the latch 84 is released, the tool holder is rotated to interchange the tools by a spring 92 (Figs. 6 and 7) in which energy has been stored up through the one-way clutch by oscillation of the shaft 14. Whatever the condition of the spring as to tension, the spring will always resist counterclockwise rotation of the tool holder when the latch is released. This spring 92 (Fig. 7) is connected at one end to a pin 94 (Figs. 7 and 9) projecting inwardly from the tool holder, and the other end of the spring is secured at 96 (Fig. 9) in a recess of a ratchet wheel 98 constituting part of the one-way clutch, the hub of said ratchet being swivelled on a bushing on the rock shaft. An advancing pawl 100 forming another part of said clutch is pivoted at 102 (see also Fig. 7) in a recess of the cup-shaped member 72 and is normally pressed by a spring 104 against the teeth of the ratchet wheel. This pawl intermittently engages the ratchet teeth for brief intervals in order to rotate the ratchet and energize the spring, and it is rendered ineffective, by mechanism to be described, when sufficient energy has been stored up in the spring 92. A retaining pawl 106 is mounted on an eccentric stud 108 projecting from the frame of the machine, a spring 110 tending to hold the pawl always in engagement with the ratchet. The eccentric mounting provides means for varying the position of the pawl so that it will properly engage the teeth.

The ratchet wheel 98 has a smooth bearing sleeve or flange 114 (Fig. 5, bottom) extending inwardly to receive mechanism for rendering the advancing pawl ineffective including a swinging carrier 116 (Fig. 5, top) provided with opposite pairs of guide flanges 118 and 120. Between the flanges at the rear of the carrier is slidably mounted a plate 122 which is slotted to embrace the bearing sleeve on the ratchet. A similar plate 124 is slidably mounted between the guide flanges 118 and 120 at the front of the carrier and the two plates are normally impelled outwardly

as far as the slots permit by a spring 130 joining the arm 126 on the slide plate 122 with the arm 128 on the slide plate 124. The slide plate 124 carries a cam 132 and the slide plate 122 has a cam 134 which is offset (Fig. 6) to lie in the same plane with the other cam. Stop lugs 140 and 142 projecting from the rear side (Fig. 15) of the ratchet wheel limit the movement of the cam 132, and similar stop lugs 144 and 146 limit the movement of the cam 134. The swinging carrier 116 with the two slide plates is normally kept at one limit of swinging movement by a spring 136 (Fig. 8) connected to the carrier and to the ratchet wheel. The slide plates and the carrier are held in assembled position by the ratchet wheel and by a washer 148 (Figs. 6 and 7) abutting against the hub of the cup-shaped member 72.

The cams are employed alternately and successively for the purpose of raising the advancing pawl from the teeth of the ratchet when the spring 92 is wound up. In the position shown in Fig. 9 the ratchet wheel is just beginning to advance under control of the pawl 100 and the oscillating shaft 14 with which the pawl is connected. As the cam 132 moves around, it contacts with a roll 150 (Fig. 7) mounted on the pivot 102 of the advancing pawl. This contact temporarily arrests the movement of the cam 132 and the swinging carrier 116, the ratchet continuing to advance and the spring 136 stretching until the lug 142 reaches the cam 132. Thereafter the cam 132, contacting with the roll 150, is pushed inwardly so as to pass under said roll, the cam face causing the plate 124 to slide radially in its guides against the tension of the spring 130. As the cam passes the roll 150, it is pulled forwardly by the spring 136 against the stop lug 140 and outwardly by the spring 130 to engage a small roll on the pivot 152 (Fig. 10) at the end of the advancing pawl 100 which is thereby raised suddenly and forcefully from the teeth of the ratchet wheel. This action prevents any further rotation of the ratchet wheel or further winding of the spring. It should be noted that opposite portions of the periphery of the ratchet wheel have the teeth interrupted for a short distance, thus insuring the stopping of the ratchet wheel after one half a revolution if for any reason the pawl tripping mechanism fails to operate. The ratchet wheel carries two opposite outwardly projecting stop pins 154 and 156 which lie in the same circle as the pin 94 projecting inwardly from the tool holder. After the parts have reached the position shown in Fig. 10, where the advancing pawl is shown out of engagement with the ratchet wheel, the latch 84 on the tool holder may be released to interchange the tools. Thereupon, the tool holder, with the pin 94 which projects inwardly from it, is caused to rotate clockwise (as viewed in Fig. 9) by 130

the spring 92 until the pin 94 engages the stop pin 154 on the ratchet, or the unwound spring pulls along the ratchet wheel forward slightly to carry the cam 132 ahead and clear of the advancing pawl 100, which is thereby allowed to return again into engagement with the ratchet teeth to wind up the spring again in preparation for a subsequent interchange of tools. On the next interchange of tools, the corresponding cam 134 and associated parts operate in a similar manner.

Mechanism is thus provided for securing a quick and easy interchange of the tools, in which the tool holder 54 is rotatably mounted upon a power-operated rock shaft 14 and is adapted, when released therefrom by depression of a manually operated latch 84 (Fig. 1), to be rotated through 180 degrees by the power of the shaft stored up in a spring 92, one end of which is secured to the tool holder at 94, and the other end of which is secured to the ratchet wheel 98 at the point 96. This ratchet wheel 98, which is held against reverse rotation by means of a retaining pawl 106 secured to the frame of the machine, is forwardly rotated intermittently, using the power of the machine itself, by means of the advancing pawl 100, which is secured to the rock shaft 14 by being mounted on the cup 72. The oscillations of the rock shaft cause the advancing pawl to move the ratchet wheel 98 along step by step until sufficient energy has been stored up in the spring 92 to effect a partial rotation of the tool carrier to interchange the tools. Inasmuch as the period of time required for this winding up of the spring will probably never exactly coincide with the period between the interchange of tools, mechanism has been provided, as above described, for rendering the advancing pawl 100 ineffective after the spring has been wound up until such a time as the tool holder has been given a partial rotation. This mechanism comprises a carrier 116, associated with which are two cam plates 122 and 124. These cam plates are normally spring pressed outwardly by a spring 130, and their cam-projections 132 and 134 lie between projections on the ratchet wheel, being held against the projections 140 and 146, as shown in Fig. 8, by a spring 136. As the ratchet wheel is advanced step by step, the cam projection 132, for example, will be brought into contact with the roller 150 occupying a fixed position in the machine. This engagement will temporarily retard forward movement of the cams and their carrier until the abutment 142 on the ratchet wheel contacts with the back face of the cam projection 132 and forces it past the roller 150. When this happens, the cam 132 will be depressed inwardly against the tension of the spring 130, and as it passes beyond the roller 150, the cam plate will be forced outwardly suddenly and forcefully to raise the advanc-

ing pawl 100 from engagement with the teeth of the ratchet wheel. As the machine is operated, the arrangement thus far described will store up energy in the spring 92, so that when the retaining latch 84 is depressed by the operator, the tool holder will be carried around to bring the next tool into operative position. As the tool holder flies around, the unwound spring 92 will tend to drag along the ratchet wheel and the cams to bring the cam 132 out of contact with the roller 150 on the advancing pawl 100, thus allowing this pawl to return into engagement with the ratchet wheel, so that energy may be again stored up in the spring for the next interchange of tools. If the cam projection has not been moved in this fashion, then the pin 94 (Fig. 7) projecting inwardly from the back side of the tool holder will engage an outwardly projecting pin 84 on the ratchet wheel and carry the ratchet wheel about the shaft to push the cam projection 132 past the advancing pawl 100. There is thus provided a self-contained mechanism associated with the tool holder, which rotates about the axis of oscillation, in which the tool holder is rotated by the power of the machine itself, the mechanism operating to transform the oscillating movements of the shaft 14 to rotary movement of the tool carrier 54. 95

At each end of the main casing 12 is secured an auxiliary casing 160 (Figs. 1 and 6) with upper and lower flat guide faces 162 (Fig. 9) for slides 166 (Fig. 6) guided and held in place by cover plates 164. The slides 166 are bent outwardly at their forward ends which are attached to brackets 168 carrying electric heating units 170. The heating units lie parallel to the edge setting irons and out of contact therewith to heat them by radiation. To vary the degree of heat, the units can be moved toward or from the edge irons by levers 174 (Fig. 3) pivoted at 172 on the auxiliary casing and having their middle portions loosely embracing pivot studs 176 (Fig. 6) projecting from the slides 166. To hold the slides frictionally in any position, springs 178 are interposed between the levers and nuts on the ends of the pivot studs 176. A shield 180 (Fig. 6), open at the sides to allow rotation of the tool holder, extends over the end of that one of the edge setting irons and its heating unit which is in the upper or inoperative position. The shield not only protects the operator from accidental contact with that iron or its heating unit but likewise retains the heat in that iron which for the moment is not in use.

In Figs. 11 and 12 is shown a floating mounting for the heating unit for the lower iron which is designed to prevent marring the work if the latter should come in contact with said heating unit or its supporting bracket. In a guideway 182 is mounted for sliding movement a slide block 184 having a

horizontal bearing opening for the reception of a rock rod 186 having a flattened portion 188 and carrying a bracket 168 and a unit 170 as does the slide 166. A spring-pressed plunger 190 has a flattened face engaging the flattened part of the shaft and, within a hollow extension 192 of the slide block 184, is mounted a spring 194 bearing at one end against the plunger and at the other end against a threaded cup 196 locked in the extension 192 by means of a lock nut 198. The slide 184 and heating unit 170 may be moved toward and from the tool in the manner described above, 200 indicating the actuating lever and 202 the pivot stud. If the work or the operator's hand should accidentally contact with the bracket 168 supporting the heating unit or the unit itself, the latter is permitted by the above described floating mounting to swing to one side to minimize the danger of injury to either and is afterward restored to its normal position by the pressure of the flattened face of the plunger 190 against the flattened face 188 of the shaft.

In using the machine the operator will adjust the position of the heating units 170 to secure the required degree of heat and will provide the machine with edge setting irons 66 and 68 shaped to fit the particular style of work to be finished. When he has completed the finishing of that part of a sole for which the proper tool is in operative position, for example the forepart, he will give the latch 84 a light tap and power supplied by the machine itself will effect an interchange of the tools to bring the shank finishing tool into position so that the shank of the shoe sole may be finished. This interchange of the tools will be effected by the spring 92 in which energy has been stored up as said spring is wound by the connections between it and the shaft involving a one-way clutch; to wit, the pawl 100 and the ratchet 98. When sufficient energy has been stored up in the spring, this clutch connection will be broken by the action of the cam plates until the tool holder has again been given a partial rotation to bring another tool into operative position. After this the one-way clutch connection will be automatically re-established and the action repeated.

Having described our invention what we claim as new and desire to secure by Letters Patent of the United States is:—

1. In a machine of the class described, in combination, a shaft, means for oscillating said shaft around its longitudinal axis, a tool holder swivelled on said shaft for intermittent turning movement around the axis of the shaft, means for locking said holder to said shaft to oscillate therewith and for unlocking it to allow rotation on the shaft, means for turning said holder, and finishing tools mounted on the tool holder for successive use as the holder is intermittently turned.

2. In a machine of the class described, in

combination, a frame, a shaft journalled in said frame and held against endwise movement therein, means for oscillating said shaft, a tool holder rotatably supported on said shaft for movement around the axis of the shaft and carrying a latch for locking the holder to said shaft to oscillate therewith, and a plurality of finishing tools carried by the holder and arranged to be brought successively into operative position upon actuation of the latch.

3. In a machine of the class described, in combination, a shaft, means for oscillating the shaft, a tool holder mounted on said shaft for intermittent rotary movement, a latch on the tool holder for locking it to the shaft to oscillate therewith, said latch extending to a point at the center of oscillation and rotation to facilitate its operation without disturbing the operator, and a plurality of finishing tools mounted on the tool holder and arranged to be brought successively into operative position upon actuation of the latch.

4. In a machine of the class described, in combination, a shaft, a tool holder having a plurality of finishing tools, a latch for locking the tool holder to the shaft, and means for oscillating the shaft and tool holder, said latch extending to a point in front of the tool holder and at the center of oscillation of the shaft to facilitate its operation without disturbing the operator.

5. In a machine of the class described, in combination, a shaft, means for oscillating the shaft, a tool holder supported by said shaft for intermittent turning movement, finishing tools oppositely mounted on the tool holder in balanced relation to the shaft, means for locking said holder to the shaft for oscillation, and means for turning the tool holder when unlocked to bring the different tools into operative positions.

6. In a machine of the class described, in combination, a shaft, means for oscillating the shaft, a tool holder swivelled on said shaft for intermittent rotation, finishing tools oppositely mounted on the tool holder for successive use, means for locking said holder to the shaft for oscillation or unlocking it, and means, independent of the operator and controlled by the machine, for rotating the tool holder a partial revolution when unlocked.

7. In a machine of the class described, in combination, a shaft, means for oscillating the shaft, a tool holder supported by said shaft for intermittent rotation, finishing tools oppositely mounted on the tool holder for successive use, means for locking said holder to the shaft for oscillation or unlocking it, and a spring, connected to the tool holder and energized by the oscillation of the shaft, for rotating the tool holder a partial revolution when the latter is unlocked.

8. In a machine of the class described, in combination, a shaft, means for oscillating

the shaft, a tool holder supported by said shaft for intermittent rotation, finishing tools mounted on the tool holder for successive use, means for locking said holder to the shaft for oscillation or unlocking it, a spring connected to the holder for rotating the holder when unlocked, and pawl and ratchet mechanism for rewinding the spring.

9. In a machine of the class described, in combination, a shaft, means for oscillating the shaft, a tool holder supported by said shaft for intermittent rotation, finishing tools mounted on the tool holder for successive use, means for locking said holder to the shaft for oscillation, a ratchet wheel on said shaft, a spring connected to the tool holder and ratchet wheel, a pawl connected to the oscillating shaft and moving the ratchet wheel step by step to wind up the spring, means for tripping the pawl, and means for retaining the ratchet wheel in position.

10. In a machine of the class described, in combination, a tool holder having a plurality of finishing tools, means for oscillating the tool holder, and means for intermittently turning the tool holder about the axis of oscillation to bring different tools into working position.

11. In a machine of the class described, in combination, a tool holder having a plurality of finishing tools, means for oscillating the tool holder, means for intermittently turning the tool holder about the axis of oscillation to bring different tools into working position, and means automatically limiting the turning movement when a tool reaches said working position.

12. In a machine of the class described, in combination, a tool holder having a plurality of finishing tools, means for oscillating the tool holder, and means intermittently energized by the operation of the machine for turning the tool holder to bring the tools successively into working position.

13. In a machine of the class described, in combination, a tool holder having a plurality of finishing tools, means for oscillating the holder, and a spring connected to the holder for automatically rotating the holder to bring the tools successively into working position.

14. In a machine of the class described, in combination, a tool holder having a plurality of finishing tools, means for oscillating the holder, and means for intermittently rotating the holder comprising a spring and means for keeping the spring under tension.

15. In a machine of the class described, in combination, a tool holder having a plurality of finishing tools, means for oscillating the holder, and means for intermittently rotating the holder comprising a spring and pawl and ratchet mechanism for winding up the spring.

16. In a machine of the class described, in combination, a tool holder having a plurality

of finishing tools, means for oscillating the holder, a spring connected to the holder for automatically rotating the holder to bring the tools successively into working position, and means actuated by the machine for winding up the spring.

17. In a machine of the class described, in combination, a rotary tool holder having a plurality of finishing tools, a spring for intermittently rotating the tool holder to interchange the tools, pawl and ratchet mechanism for energizing the spring, and a cam carried by the ratchet for tripping the pawl.

18. In a machine of the class described, in combination, a rotary tool holder having a plurality of finishing tools, a ratchet wheel, a spring connecting the tool holder and the ratchet wheel, a pawl, means for oscillating the pawl to turn the ratchet wheel, and a cam connected to the ratchet wheel for releasing the pawl.

19. In an edge setting machine, in combination, a shaft, means for rocking the shaft, a tool holder secured to said shaft, and a plurality of edge setting tools yieldingly mounted on said holder and arranged on opposite sides of said shaft to balance each other, each tool having its longitudinal axis arranged at a small angle to the tool holder to present the working end in the desired position when the tool is in use.

20. In an edge setting machine, in combination, a horizontal rock shaft, means for rocking the shaft, a plurality of edge setting tools each connected to the shaft with its longitudinal axis tipped forwardly to present its working end in proper working position, and means for intermittently turning said tools around the shaft to bring them successively into similar operative positions.

21. In an edge setting machine, in combination, a horizontal rock shaft, means for rocking the shaft, a tool holder mounted on each end of the shaft at right angles thereto for oscillating movement with the shaft or rotation about the axis of the shaft, and a plurality of edge setting tools yieldingly carried by each tool holder at an inclination thereto.

22. In an edge setting machine, in combination, a rock shaft, means for rocking the shaft, a tool holder on said shaft, and means for locking the tool holder to the shaft and unlocking the same to allow it to be turned around the shaft.

23. In an edge setting machine, in combination, a rock shaft, means for oscillating the rock shaft, a tool holder secured to the shaft to rock therewith, edge setting irons mounted in the tool holder on opposite sides of the shaft, and springs interposed between the irons and the holder to cushion the tools against pressure of the work.

24. In an edge setting machine, in combination, a symmetrical tool holder, means

for rocking the tool holder about its axis, edge setting irons mounted on opposite sides of the tool holder, and springs interposed between the irons and the holder to cushion the tools against pressure of the work.

25. A machine of the character described, having, in combination, a frame, an idle tool, means for moving the tool to operative position, a slide mounted on the frame, an electric heating unit secured to the slide near the path of movement of the tool to heat the tool by radiation, a shield partially enclosing the tool and the unit, and means for moving the slide and the unit toward and from the tool to control the amount of heat transmitted to said tool.

26. In an edge setting machine, in combination, a frame, an edge setting tool, means for rapidly oscillating the tool, a slide mounted on the frame, an electric heating unit secured to the slide near the path of movement of the tool to heat the tool by radiation, manually operable means for moving the slide and the unit toward and from the tool to control the amount of heat transmitted to said tool, and a friction member for holding the slide in adjusted position.

27. In an edge setting machine, in combination, a tool holder, means for oscillating the tool holder, a pair of edge setting irons carried by the holder and arranged to be brought successively into working position, an electric heating unit mounted adjacent to each iron, and a shield enclosing that heating unit which is adjacent to the iron not in use.

28. In an edge setting machine, in combination, a tool holder, means for oscillating the tool holder, a pair of edge setting irons carried by the holder and arranged to be brought successively into working position, an electric heating unit mounted adjacent to that iron which is not in use to keep the iron hot and ready for use, and a shield enclosing both the heating unit and the iron.

29. In an edge setting machine, in combination, a tool holder, means for oscillating the tool holder, a pair of edge setting irons carried by the holder and arranged to be brought successively into working position, and a shield enclosing one of said setting irons to protect the operator and being open at the sides to allow turning of said iron to an operative position.

30. In an edge setting machine, in combination, an edge setting tool, means for oscillating the tool, an electric heating unit mounted near the path of movement of the tool to heat the tool by radiation, and a swivel mounting for the heating unit to allow it to turn to prevent damage to the work.

31. In an edge setting machine, in combination, an edge setting tool, means for oscillating the tool, normally stationary heating means for the tool, and a floating support for the heating means to allow displacement of

the heating means by accidental contact with the work or the operator.

32. In an edge setting machine, in combination, an edge setting tool, means for oscillating the tool, normally stationary heating means for the tool, a rockable shaft supporting the heating means, and means cooperating with the shaft to hold the heating means yieldingly in normal position.

33. In an edge setting machine, in combination, an edge setting tool, means for oscillating the tool, normally stationary heating means for the tool, supporting means for the heating means comprising a rockable shaft having a flattened portion, and a spring-pressed member engaging the flattened portion to hold the shaft and heating means yieldingly in normal position.

34. In an edge setting machine, in combination, a tool holder having a plurality of edge setting tools, means for oscillating the tool holder to cause the tools to rub the work, and means for automatically rotating the tool holder to bring the tools into working position, said rotating means being rendered effective by mere unlocking of the tool holder from the oscillating means.

35. In an edge setting machine, in combination, a tool holder having a plurality of edge setting tools, means for oscillating the tool holder to cause one of the tools to rub the work, means constantly tending to rotate the tool holder, and a latch for preventing said rotary movement and operable by a light tap to release said holder to bring the tools successively into working position.

36. A machine of the character described, having, in combination, a tool holder, a plurality of tools carried by the holder, means for actuating the holder to cause one of the tools to treat the work, and a spring energized by the actuating means for rotating the holder and bringing the tools successively into working position.

37. A machine of the character described, having, in combination, a plurality of shoe treating tools, means for actuating said tools to treat the work, a spring for successively bringing the tools to working position, and means for keeping the spring under tension.

38. In a machine of the class described, a rotatably mounted holder supporting a plurality of shoe-finishing tools, a power-operated shaft for driving said tools, means including a one-way clutch for utilizing the power of said shaft to shift the holder to bring the tools alternately into operative position, and means controlled by the operator for preventing operation of the shifting means.

39. In a machine of the class described, a rotatably mounted holder supporting a plurality of shoe-finishing tools, a power-operated shaft for driving said tools, means including a one-way clutch for utilizing the

power of said shaft to shift the holder to bring the tools alternately into operative position, and means for rendering said clutch ineffective.

40. In a machine of the class described, a rotatably mounted holder supporting a plurality of shoe-finishing tools, a power-operated shaft for driving said tools, means including a one-way clutch for utilizing the power of said shaft to move the holder to bring the tools alternately into operative position, means for rendering said clutch ineffective, and means for locking said holder in operative position.

41. In a machine of the character described, a movable holder supporting a plurality of shoe-finishing tools, a power-operated shaft, means for transmitting the power of said shaft to one of said tools to give it a shoe-finishing movement, means including a one-way clutch for moving said holder to bring another tool into operative position, and means for rendering said clutch ineffective.

42. In a machine of the class described, a shaft, a holder supporting a plurality of shoe-finishing tools rotatably mounted in said machine concentrically with said shaft, means for transmitting the movements of the shaft to one of the finishing tools, and means including a one-way clutch for moving said holder to bring another tool into operative position.

43. In a machine of the character described, a power-operated shaft, a rotatable holder supporting a plurality of shoe-finishing tools mounted concentrically with said shaft, means for oscillating said shaft through a narrow arc, means for interconnecting said tool holder and said shaft to transmit the oscillations of the shaft to the tool which is in operative position, and means including a one-way clutch for causing the cumulative oscillations of the shaft to produce a larger arc of movement of the tool holder at the will of the operator to interchange the tools and bring another tool into operative position.

44. In a machine of the class described, in combination, a shaft, means for oscillating the shaft, a tool holder supported by said shaft for intermittent turning movement, finishing tools oppositely mounted on the tool holder in balanced relation to the shaft, means for locking said holder to the shaft for oscillation, and means for transforming the oscillating movements of the shaft into a rotary movement of the tool holder when the locking means is released.

45. In a machine of the class described, in combination, a shaft, means for oscillating the shaft, a tool holder swivelled on said shaft for intermittent rotation, finishing tools oppositely mounted on the tool holder for successive use, means for locking said holder to the shaft for oscillation or unlocking it, and means, independent of the operator and con-

trolled by the machine, for transforming the oscillating movements of the shaft into a partial rotation of the tool carrier when the locking means is unlocked.

46. In a machine of the class described, in combination, a tool holder having a plurality of finishing tools, a shaft, means for oscillating said shaft, and connecting means between the shaft and the tool holder constructed and arranged intermittently to transform the oscillating movements of the shaft into a partial rotation of the tool holder about the axis of oscillation to bring different tools into working position.

47. In a machine of the class described, in combination, a tool holder having a plurality of finishing tools, means for oscillating the tool holder, and means intermittently rendered effective to transform the tool-actuating movements of the tool holder into tool-interchanging movements of the holder.

48. In a shoe finishing machine, a power-driven shaft, a holder carrying a plurality of shoe finishing tools and mounted for rotational movement around said shaft about an axis substantially coinciding with the axis of said shaft, means for detachably connecting the holder to the shaft, and connections between the shaft and holder constructed and arranged to deliver to the holder power derived from movement of the shaft and effective to move the holder around the shaft to move one tool out of and another tool into working position when the holder is disconnected from the shaft.

49. In a shoe finishing machine, a rock shaft, a holder carrying a plurality of shoe finishing tools and mounted for rotational movement around said shaft about an axis substantially coinciding with the axis of said shaft, means for detachably connecting the holder to the shaft, and connections between the shaft and holder constructed and arranged to deliver to the holder power derived from movement of the shaft in one direction and effective to move the holder around the shaft to move one tool out of and another tool into working position when the holder is disconnected from the shaft.

50. In a shoe finishing machine, a rock shaft, means for oscillating the rock shaft, a holder carrying a plurality of edge setting tools and mounted for rotational movement about said rock shaft on an axis substantially coinciding with the axis of the rock shaft, means for detachably connecting the holder to said shaft to oscillate with the shaft, and connections between the shaft and holder constructed and arranged to deliver to the holder power derived from the rock shaft during movements of the shaft in one direction and effective to move the holder around the shaft to move one edge setting tool out of and another edge setting tool into working

position when the holder is disconnected from the shaft.

51. In a shoe finishing machine, a power driven shaft, a holder carrying a plurality of edge setting tools and mounted for rotational movement around said shaft on an axis substantially coinciding with the axis of the shaft, means for detachably connecting the holder to said shaft, manually controlled means for disconnecting the holder from the shaft, and connections between the shaft and holder constructed and arranged to deliver to the holder power derived from movement of the shaft and effective to move the holder 10 around the shaft to move one tool out of and another tool into working position when the holder is disconnected from the shaft.

52. In a machine for operating upon shoes, a movable tool holder provided with a plurality of finishing tools arranged for use one at a time, means for locking said holder in operative position, means for moving the holder to bring another tool into position comprising an actuating spring, a ratchet arranged to be operated to tension the spring, and a pawl for moving the ratchet, and means for disengaging the pawl when the spring has been brought to the desired tension.

53. In a machine for operating upon shoes, a movable tool holder provided with a plurality of finishing tools arranged for use one at a time, means for locking said holder in operative position, means for moving the holder to bring another tool into position comprising an actuating spring, a ratchet arranged to be operated to tension the spring, and a pawl for moving the ratchet, and means for disengaging the pawl when the spring has been brought to the desired tension comprising a sliding cam member, and means for reciprocating said cam member to lift the pawl.

54. In a shoe finishing machine, an oscillating rock shaft, a tool holder rotatably mounted on said rock shaft, a housing secured to said rock shaft adjacent to said tool holder, the rim of said housing forming a flange which is recessed to provide a notch, means on said tool holder arranged detachably to engage said flange in said notch, thereby to lock the tool holder to the housing and the shaft, and means concealed within said housing and constructed and arranged to transform the oscillations of the rock shaft into a turning movement of the tool holder when it is released from the housing.

55. In a shoe finishing machine, an oscillating rock shaft, a tool holder rotatably mounted on said rock shaft adjacent to the end thereof and having a locking part, a housing secured to said rock shaft having an open end adjacent to the tool holder provided with a flanged rim upon which the tool holder locking part slides as the tool holder rotates, the flanged rim of said housing having

notches to cooperate with said locking part to secure the tool holder in operative positions with respect to the shaft, and resilient means urging said part into one of said notches.

56. In a shoe finishing machine, an oscillating rock shaft, a rotatably mounted holder supporting a plurality of shoe finishing tools, means for detachably connecting the holder to the shaft for oscillation therewith, said holder being mounted for rotation about the axis of the shaft, means for transforming the oscillatory movements of the shaft into a rotary movement of the tool holder, and operator controlled means for releasing the tool holder to permit its rotation.

57. In a shoe finishing machine, an oscillating rock shaft, a holder rotatably mounted on said shaft supporting a plurality of shoe finishing tools, means for detachably connecting the holder to the shaft for oscillation therewith, means resisting rotation of the tool holder in one direction, and operator controlled means for releasing the holder for rotation in the opposite direction so that another tool may be brought into operative position.

58. In a shoe finishing machine, a movable tool holder for a plurality of shoe finishing tools adapted to be brought alternatively into operative position, means for detachably holding said tool holder against the tool interchanging movement, and means comprising an oscillatory shaft and a one-way clutch for moving said tool holder when released to change the tools.

59. In a shoe finishing machine, a tool holder having a plurality of finishing tools, a shaft for oscillating the tool holder, said tool holder being rotatably supported for tool interchanging movement about an axis substantially coincident with the axis of said shaft, automatic means utilizing power derived from the shaft constructed and arranged to effect a tool interchanging movement, and operator controlled means for releasing the tool holder to permit such movement.

60. In a machine of the class described, a rotatably mounted holder supporting a plurality of shoe-finishing tools, a power-operated shaft for driving said tools, said tools being positioned symmetrically with respect to said shaft, means including a one-way clutch for utilizing the power of said shaft to shift the holder to bring the tools alternatively into operative position, and means controlled by the operator for preventing operation of the shifting means.

In testimony whereof we have signed our names to this specification.

ARTHUR W. BRICE.
WILLIAM HAMANN.
